20 Claims. (Cl. 66—130)

The present invention relates to shock absorbing apparatus for braking a reciprocating member near the ends of its stroke, and more particularly to shock absorbing apparatus for braking and stopping the yarn carrier means of a straight bar knitting machine.

Straight bar knitting machines of the "Cotton" type, have yarn carriers connected with friction boxes mounted on a reciprocable friction box rod. When knitting machines of this type are operated at high speed and during the knitting of wide work pieces, it is necessary to brake the movement of the yarn carrier means before the same are stopped by stop means at the ends of the desired strokes.

It is advantageous to reduce the speed of the yarn carrier means gradually from the maximum speed to zero speed, and in one construction according to the prior art, the carrier rod of the yarn carrier is driven by a crank which performs a movement through 90° so that at the end of the stroke, the crank moves transverse to the direction of movement of the carrier rod, so that the same is not driven in its end position.

However, this prior art construction has the disadvantage that the yarn carrier means must move at least a distance corresponding to four times the radius of the crank movement. Under practical conditions, it is very frequently necessary to knit webs of lesser width.

Therefore, another construction of the prior art uses a friction coupling between driving means and the carrier rod, permitting the knitting of narrower workpieces. The shock absorbing effect is obtained by moving the friction coupling in the opposite direction before the carrier means have engaged the stop at the end of the reciprocating stroke.

Another construction serving this purpose is disclosed in the British Patent 899,345. This apparatus requires a very careful adjustment, and it has been found that even very minute deviations from the adjusted position, as will occur after the machine has been operated for a certain time, may result in disturbance of the operation, and even in breakage of parts of the coulier motion.

It is one object of the present invention to overcome the disadvantages of known shock absorbing apparatus, particularly as used in straight bar knitting machines, and to provide a shock absorbing apparatus which reliably operates to brake and stop a reciprocating member, such as yarn carrier means, at the ends of reciprocating strokes.

Another object of the invention is to provide a shock absorbing apparatus in which an engaging member coupled to a control shaft rotating at a selected speed, is turned by the reciprocating member through such an angle that the speed of the reciprocating member is gradually reduced.

Another object of the invention is to provide a shock absorbing apparatus for the yarn carrier means of a straight bar knitting machine which will reliably operate when the stroke of the coulier motion is adjusted to different widths of the knitted fabric.

With these objects in view, the present invention relates to a shock absorbing apparatus which is particularly suited for braking and stopping the yarn carriers of the straight bar "Cotton" type knitting machine. One

2

embodiment of the invention comprises a control shaft rotated at a selected speed; supporting means; shock absorbing means mounted on the supporting means for turning movement and connected by an overrunning clutch with the control shaft; and a reciprocable member, such as the friction box by which the yarn carrier means are reciprocated, and being reciprocated in one direction at a speed having a predetermined ratio to the speed of the control shaft. Near the end of each reciprocating stroke, 10 the shock absorbing means are engaged by the reciprocating member and turn at such a speed that the overrunning clutch is engaged. In this condition of the clutch, the control shaft turns the shock absorbing means at a selected speed so that the speed of further movement 15 of the reciprocating member cannot exceed the speed component of the rotary speed of the shock absorbing means in the direction of movement of the reciprocating member.

The shock absorbing means include an engaging member 20 moving along a circular path through an angle of substantially 90°. When the engaging member is first engaged by the reciprocating member, it moves out of a first angular position substantially in the direction of reciprocation, but when engaging member with the shock 25 absorbing means is turned through 90° until direction of movement of the engaging member is transverse to the direction of reciprocation, the reciprocating member is stopped. In this manner, the speed of the reciprocating member is gradually reduced from its maximum speed 30 to zero speed.

Biassing means normally hold the overrunning clutch in a position of rest in which it is disengaged, and the force of the biassing means is overcome by the force of the reciprocating member.

35 In the preferred embodiment of the invention, a lever is mounted on the supporting means, and the engaging member of the shock absorbing means is not directly engaged by the reciprocating member for example by the friction box, but the reciprocating member engages the force-transmitting lever and presses the same against the engaging member so that the same slides or rolls on the force transmitting lever while moving through 90° from its first angular position to its second angular position.

45 During the turning movement of the shock absorbing means, the reciprocating friction box is braked since the engaging member of the shock absorbing means moves along the circular path at a constant speed determined by the control shaft.

In one embodiment of the invention, the overrunning clutch is connected by bevel gears to the control shaft, and the supporting means with the shock absorbing means and the overrunning clutch, are adjustable in the 55 direction of reciprocation so that the control shaft is provided with axial grooves to permit an axial movement of the bevel gear mounted thereon, while the bevel gear is connected to the control shaft for turning movement.

Straight bar knitting machines in which the reciprocating stroke produced by the coulier motion is substantially constant, permit the driving of the control shaft from the main drive shaft of the machine, or from the cam shaft of the machine through a transmission which is designed so that the speed of the engaging member along its circular path is equal to the speed of reciprocation of the friction boxes and yarn carriers.

Straight bar knitting machines in which the stroke of the coulier motion is adapted to different fabric width, require the control shaft to be driven at a speed directly 60 depending on the speed of reciprocation of the coulier motion, and in machines of this type, the present invention provides a transmission between a reciprocating

member driven in a synchronism with the coulier motion, and the control shaft so that the speed of rotation of the control shaft corresponds to the speed of reciprocation produced by the coulier motion, which is different for different fabric widths.

One embodiment of this construction provides a reversing gear which is automatically operated to connect a reciprocating member with the control shaft in such a manner that the control shaft always rotates in the same direction although the reciprocating member moves in opposite directions. The reversing gear is automatically shifted under the control of a cam rotating in synchronism with the draw cam or coulier cam of the machine.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary front elevation of a shock absorbing apparatus according to the present invention;

FIG. 2 is a fragmentary sectional view taken on line II-II in FIG. 1;

FIG. 3 is a fragmentary plan view of the embodiment shown in FIGS. 1 and 2;

FIG. 4 is a fragmentary front view illustrating a detail of FIG. 1 on an enlarged scale;

FIG. 5 is a fragmentary, partly schematic, cross-sectional view illustrating a straight bar knitting machine of the "Cotton" type in which the yarn carrier means are braked and stopped by the shock absorbing apparatus of the invention;

FIG. 6 is a fragmentary rear view illustrating a modified construction of the invention particularly suited for straight bar knitting machines in which the stroke of the coulier motion is adjustable in accordance with the fabric width; and

FIG. 7 is a fragmentary schematic cross-sectional view illustrating a straight bar knitting machine provided with the embodiment of the invention shown in FIG. 6, with parts illustrated in FIG. 5 omitted for the sake of simplicity.

Referring now to the drawings, and more particularly to FIG. 5, the standard parts of a straight bar knitting machine of the "Cotton" type are only schematically indicated, while parts cooperating with the apparatus of the present invention are shown in detail. The machine has a plurality of walls 29, indicated in chain lines in FIG. 5 which are connected by longitudinal beams 30, 31, 32 and 33 and which support a plurality of shafts and rods extending longitudinally of the machine, and indicated in cross section. A motor 34 is connected by a pulley and belt drive 35 to a pulley 36 fixed to a shaft 37 carrying a gear 40 meshing with a larger gear 39 secured to the cam shaft 38 of the machine on which several cams, not shown, are mounted by which the knitting motions of the needles and other operations of the machine are controlled in a well known manner. A bevel gear 41 is secured to cam shaft 38 and meshes with another bevel gear 42 secured to the coulier shaft 25 which is mounted in a bearing 43 on connecting beam 31 and carries at its free end a coulier or draw cam 44.

Connecting beam 31 carries a supporting stud 45 on which a draw lever or rocker arm 46 is mounted for reciprocating angular motion. Rocker arm 46 carries a pair of horizontally spaced cam follower rollers 47 of which only one is shown in FIG. 5, and which are arranged on opposite sides of the draw cam 44 to serve as cam followers. During turning movement of draw cam 44, rocker arm 46 will perform an angular reciprocating coulier motion. The sinkers and the yarn carrier means are operated in accordance with this motion.

The upper end of rocker arm 46 is connected by a

bearing 46a and a pin therein to a bracket 48 which is secured to the connecting bar 49a on which a slur cam box 50 is mounted for each section of the machine. The slur cam box 50 is supported for sliding movement on the slur cam box bar 49, and will reciprocate along the same under the control of draw cam 44. The slur cam box 50 has a slur cam cooperating with the jacks 51 which are pivoted on a shaft 52 and respectively cooperate with sinkers 53 which are successively advanced when the slur cam moves longitudinally of the machine in accordance with the coulier motion.

The reciprocating connecting bar 49a carries several brackets 54 on which the friction box rod or splicing shaft 51 is mounted so that the same reciprocates with the coulier motion.

As also shown in FIGS. 1 to 4, friction box 2 is connected by the friction box slide 3 to the carrier rod 4 on which yarn carrier 55 is mounted. The frictional engagement between the friction box 2 and the friction box rod 1 is sufficient to cause reciprocating movement of the yarn carrier means 4, 55. However, the frictional coupling between friction box 2 and friction box rod 1 permits it to stop the yarn carrier means before friction box rod 1 has reached the end of its reciprocating stroke since the friction box of the stopped yarn carrier will slide on the moving friction box rod 1.

The end positions of the yard carrier means are determined by a stop 4a on carrier rod 4 which cooperates with a pair of adjustable stop means 5 and 6. Stop means 5 and 6 are mounted on threaded spindles 5' and 6', respectively, and are adjustable for determining the end positions of stop 4a, and of the yarn carrier means. If stop 4a engages either stop means 5 or stop means 6, yarn carrier rod 4 may slide in yarn carrier slide 3.

A cylindrical guide bar 17 extends longitudinally of the machine and is supported on bracket 17a on beam 32, as shown in FIG. 2. A pair of slideable supporting means 7 and 8 are mounted on guide bar 17 for longitudinal sliding movement, and are respectively connected by spacing rods 5a and 6a to the adjustable stop means 5 and 6 so that the distance between supporting means 7 and 8 is adjusted when the distance of stop means 5 and 6 is adjusted.

Each supporting means 7 and 8 supports a shock absorbing means including a circular disk 11b secured to a shaft 11 which is journaled in the respective supporting means and carrying a stud 11a on which a roller 10 is mounted for turning movement so that roller 10 moves along a circular path when shock absorbing means 11, 11a, 11b, 10 turns. The end of shaft 11 is secured to the inner part 12 of an overrunning or one-way clutch 13 whose outer part is secured to a bevel gear 14. A spring 7a is secured to each supporting means 7 and 8 and to an eccentric point of the inner part 12 of the overrunning clutch 13, so that clutch 13 is normally disengaged and in a position of rest, as will be explained hereinafter. The overrunning clutch 13 may be of the conventional construction in which rollers are mounted in wedge-shaped spaces between the outer and inner parts of the clutch.

Each supporting means 7 and 8 carries a force transmitting lever 9 which has an end portion located in the path of movement of friction box 2, and adapted to be engaged by the same during reciprocating movement of friction box rod 1, as shown for the left lever 9 in FIG. 1.

When lever 9 is not engaged by the friction box, it is turned by the engaging member 10, 11a inwardly toward friction box 2 since spring 7a turns engaging member 10, 11a of the right shock absorbing means in counter-clockwise direction, and engaging member 10, 11a of the left shock absorbing means in clockwise direction, as viewed in FIG. 1. Since the right lever 9 is not engaged by the friction box 2, it is turned by engaging member 10, 11a to a position engaging an adjustable stop 56 on supporting means 8.

In this position of lever 9, the overrunning clutch 13 is in a disengaged position of rest, and engaging member 10, 11a is in such a position that a plane passing through stud 11a and the center of shaft 11 will extend transverse to the direction of reciprocation of friction box 2 which is also the longitudinal direction of friction box rod 1.

When the right lever 9, engaged by friction box 2 is turned in counterclockwise direction, or when the left lever 9 is turned by the friction box 2 in clockwise direction, the respective lever presses against engaging member 10, 11a and turns the shock absorbing means 11, 11a, 11b, 10 together with the inner part 12 of the overrunning clutch against the action of the respective spring 7a to a position in which a plane passing through stud 11a and the center of shaft 11 is parallel to the direction of reciprocation, as shown for the left shock absorbing means in FIG. 1. Since in this position of lever 9, no turning moment is exerted on shock absorbing means 11, 11a, 11b, 10, engaging member 10, 11a constitutes a stop which prevents further turning of lever 9 and consequently stops friction box 2 so that friction box rod 1 slides in friction box 2 when continuing its reciprocating motion.

It will be seen that engaging member 10, 11a would have to move further along its circular path transverse to the direction of reciprocation of friction box 2, which is not possible. On the other hand, engaging member 10, 11a on the right of FIG. 1 will start its movement along its circular path in a direction parallel to the reciprocating motion of friction box 2 when the same engages lever 9, and consequently will tend to move at the same speed as friction box 2. The speed component of the speed of engaging member 10, 11a along its circular path is equal to the speed of reciprocation in the first angular position of engaging member 10, 11a shown on the right of FIG. 1, and is zero for the second angular position of engaging member 10, 11a shown on the left of FIG. 1.

As shown in FIGS. 2, 3 and 5, a control shaft 16 is mounted in bearings of bracket 17a, and extends parallel to the direction of reciprocation and to guide bar 17. Control shaft 16 has longitudinal axially extending grooves 16 and carries a bevel gear 15 which has projections cooperating with the grooves of the shaft so that bevel gear 15 is shiftable in axial direction of the shaft, but turns with the same. A hub portion of bevel gear 15 is mounted in a bearing on an arm 7b of supporting means 7, as shown in FIG. 3 so that bevel gear 15 is moved along the splined control shaft 16 when the position of supporting means 7 is adjusted along guide bar 17. A corresponding arrangement is provided for supporting means 8, so that the overrunning clutch of the shock absorbing means 11, 11a, 11b, 10 is also driven from control shaft 16.

As shown in FIG. 5, a sprocket 57 is secured to shaft 37 and connected by a chain 58 to a sprocket 59 secured to control shaft 16. Since the reciprocating motion of friction box rod 1 is also derived from shaft 37 through gears 39, 40, shaft 38, gears 41, 42 and cam 44, the rotary speed of control shaft 16 is in a certain ratio to the reciprocating speed of friction box 2, and can be selected by suitably designing the transmission means.

The rotary speed of control shaft 16 is selected in such a manner that the outer part of overrunning clutch 13 rotates at the same speed at which shaft 11 turns with the inner part 12 of the overrunning clutch when lever 9 is engaged by friction box 2 and turns engaging member 10, 11a out of its first angular position shown on the right side of FIG. 1.

Consequently the moment in which friction box 2 engages lever 9 near the end of the reciprocating stroke of yarn carrier means 4, 55, the inner part 12 of the overrunning clutch is driven at the same rotary speed as the outer part, and consequently the overrunning clutch 13 engages and shock absorbing means 11, 11a, 11b, 10 continues its turning movement at the same speed as control shaft 16 with which it is now positively coupled, and

the rotary speed of shaft 11 cannot exceed the rotary speed of control shaft 16.

While engaging member 10, 11a moves from its first angular position shown on the right of FIG. 1 to its second angular position shown on the left of FIG. 1, engaging member 10, 11a moves along 90° of a circular path, but the end of lever 9 moves substantially in the direction of reciprocation of friction box 2 so that the speed of the friction box corresponds only to a component of the speed of engaging member 10, 11a along the circular path, namely the component in the direction of the reciprocating movement.

As explained above, this component is substantially equal to the reciprocating speed in the first angular position of engaging member 10, 11a shown on the right of FIG. 1, and is zero in the second angular position of engaging member 10, 11a shown on the left of FIG. 1 where the end of the reciprocating stroke is reached. At the same time, the angular speed of lever 9 is reduced from a maximum to zero. Consequently, the movement of friction box 2 is retarded and its speed is gradually reduced to zero so that the yarn carrier means 4 is stopped without any shock.

The machine is prepared for the operation by adjusting the positions of stop means 5 and 6 together with the positions of supporting means 7 and 8 in accordance with the desired length of the reciprocating stroke of yarn carrier means 4, 55. When the machine is operated, the coulier motion derived from draw cam 44 causes reciprocation of the slur cam boxes 50 with the slur cams whereby the sinkers 53 are advanced, and simultaneous reciprocation of the friction box rod 1 with the friction boxes 2 and yarn carrier means 4, 55. The length of the reciprocating stroke of friction box rod 1 corresponds to the reciprocating stroke required for the slur cam, and is greater than the length of the reciprocating stroke desired for the yarn carrier 55.

During the greater part of the reciprocating stroke of yarn carrier means 4, 55, the shock absorbing means are in the position shown on the right of FIG. 1 for the shock absorbing means mounted on supporting means 8. Spring 7a, not shown in FIG. 1, turns the shock absorbing means with engaging member 10, 11a to urge levers 9 inward against stops 56. The overrunning clutch 13 is disengaged in this position so that the inner part 12 is stopped and the outer part of the overrunning clutch 13 is driven through bevel gears 14, 15 from control shaft 16 at a selected speed.

When friction box 2 is near the end of a reciprocating stroke, it engages the respective lever 9 and turns the same about its pivotal support on the supporting means 7 or 8 so that engaging member 11a starts its movement along its circular path parallel to the direction of reciprocation at a speed corresponding to the circumferential speed of the outer part of the overrunning clutch so that the same is engaged, and the speed of engaging member 10, 11a along its circular path cannot exceed the rotary speed of the outer part of the overrunning clutch 13 which depends on the rotary speed of control shaft 16.

The respective engaging member 10, 11a gradually approaches the position shown for the shock absorbing means on supporting means 7 in FIG. 1, while the angular speed of lever 9 is reduced to zero due to the fact that the component of the speed of the engaging member along its circular path which acts in the direction of reciprocation is gradually reduced to zero, and is zero when engaging member 10, 11a moves transverse to the direction of reciprocation. Roller 10 rolls on the engaging face of the force transmitting lever 9 during movement from its first angular position to its second angular position. In the latter position lever 9 is blocked, and stops friction box 2 so that friction box rod 1 slides in friction box 2 during further reciprocating movement of friction box rod 1 under the control of rocker arm 46. Stop means 5 and

6 determine the limits of the reciprocating stroke of the yarn carrier rod 4 when engaged by stop 4a.

The embodiment of the invention described with reference to FIGS. 1 to 5 is concerned with a machine in which the coulier distance is constant, corresponding to a fabric of constant width. Since the speed of reciprocation is constant, it is possible to drive control shaft 16 from the main drive shaft 37 from which the speed of the reciprocating elements is also derived.

The embodiment illustrated in FIGS. 6 to 7 corresponds in every respect to the embodiment described with reference to FIGS. 1 to 5 but is modified for a machine in which the coulier distance varies and is automatically adjusted to the width of the knitted fabric. Under such operational conditions, the coulier speed is not in a fixed ratio to the rotary speed of the main drive shaft and of the cam shaft of the machine, but the ratio varies when the coulier distance and length of reciprocating stroke is varied. Assuming the constant speed of the main drive shaft and cam shaft, the coulier speed is reduced when the width of the knitted fabric is reduced.

The shock absorbing apparatus according to the present invention requires that the rotary speed of control shaft 16 is always in a certain predetermined ratio to the coulier speed, and to the speed of reciprocation of the yarn carrier means. Consequently, control shaft 16 cannot be directly driven from the main drive shaft or cam shaft of the machine as described with reference to FIG. 5, but must be driven at a rotary speed corresponding to the speed of reciprocation of the friction box rod 1. However, since friction box rod 1 moves in opposite directions while reciprocating, a direct transmission between friction box rod 1 and control shaft 16 would cause alternate rotation of control shaft 16 in opposite direction, and in accordance with the present invention, reversing gear means are provided.

As shown in FIGS. 6 and 7, a rack bar 18 is secured to friction box rod 1 for reciprocation at the same speed. A gear 19 is mounted in a suitable bearing of beam 32, and meshes with rack bar 18 so that it is turned in opposite directions during reciprocating strokes of friction box rod 1 with rack bar 18. A bevel gear 20 is secured to gear 19 and turns with the same. Bevel gears 21 and 22 mesh with bevel gear 20 and are mounted for turning movement on cylindrical portions of the splined control shaft 16. Bevel gears 21 and 22 cannot be simultaneously connected to control shaft 16, since they rotate in opposite directions while each bevel gear 21 and 22 changes its direction of reciprocation in accordance with the directions of the reciprocating strokes of rack bar 18. Each bevel gear 21 and 22 has a coupling portion cooperating with a corresponding coupling portion 23 or 24, coupling portions 23 and 24 being connected by a yoke 28. Each coupling means 23 and 24 has projections engaging the grooves in control shaft 16 so that coupling means 23 and 24 are connected with control shaft 16 for rotation therewith and are shiftable thereon in axial directions. Coupling means 23 and 24 are turnably mounted in yoke 28, so that shifting of yoke 28 with coupling means 23 and 24 to the right as viewed in FIG. 6 will cause coupling means 23 to engage with its coupling fingers the corresponding coupling part on bevel gear 21 so that the same is coupled with control shaft 16 for rotation therewith whereby control shaft 16 is rotated at the rotary speed depending on the speed of reciprocation of friction box rod 1 and rack bar 18. When yoke 28 with coupling means 23, 24 is shifted to the left as viewed in FIG. 6, coupling means 23 is disengaged, and coupling means 24 is engaged so that control shaft 16 is now driven through bevel gear 22, instead of through bevel gear 21 as before. Coupling means 28, 23, 24, and more particularly yoke 28 is pivotally connected to the end of a cam follower lever 27 which is mounted on a bearing bracket on beam 32. The end of cam follower lever 27 carries a cam follower roller cooperating with an auxiliary cam 26 secured to coulier shaft

25 on which draw cam 44 is mounted, as best seen in FIG.

7. As explained above, the reciprocating motion of friction box rod 1, and of rack bar 18, is derived from draw cam 44 and depends on the rotary speed of coulier shaft 5 25. Auxiliary cam 26 rotates at the same speed as draw cam 44, and its shape is designed in such a manner that cam follower lever 27 is reciprocated in timed relation with the reciprocating motion of friction box rod 1 and rack bar 18. Whenever friction box rod 1 and rack bar 18 arrive at the end of a reciprocating stroke and reverse the direction of movement, coupling means 28, 23, 24 is shifted. Since bevel gears 21, 22 reverse the direction of rotation in synchronism with the reciprocation of rack bar 18, and since they are coupled in synchronism with the 10 same reciprocating movement, control shaft 16 is coupled alternately to bevel gears 21 and 22 in such a manner as to always rotate in the same direction of rotation at a speed which depends on the speed of reciprocation of friction box rod 1.

20 As explained with reference to the embodiment of FIGS. 1 to 5, the rotary speed of control shaft 16 must be in a selected ratio to the speed of reciprocation of the friction box rod 1, and this is accomplished in the embodiment of FIGS. 6 and 7 by driving control shaft 16 25 from the coulier shaft 25 rather than from the main drive shaft 37 which is necessary in machines where the speed of the coulier shaft 25 varies in relation to the speed of the main shaft 37 in accordance with the width of the knitted fabric.

30 It will be understood that each of the elements described above, or two or more together, may also find a useful application in other types of shock absorbing apparatus differing from the types described above.

While the invention has been illustrated and described 35 as embodied in a shock absorbing apparatus for the yarn carrier means of a straight bar knitting machine, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various 40 applications without omitting features that, from the standpoint of prior art, fairly constitute essential characteristics of the generic or specific aspects of this invention and, therefore, such adaptations should and are intended to be comprehended within the meaning and range of equivalence of the following claims.

50 What is claimed as new and desired to be secured by Letters Patent is:

1. Shock absorbing apparatus comprising, in combination, control shaft means; means for rotating said control shaft means at a selected speed; supporting means; shock absorbing means mounted on said supporting means for turning movement; an overrunning clutch connecting said shock absorbing means with said control shaft means and having a position of rest in which said overrunning clutch is disengaged; and a reciprocable member driven to move 55 in one direction at a speed having a predetermined ratio to said selected speed of said control shaft means and engaging said shock absorbing means near the end of a reciprocating stroke whereby said shock absorbing means is turned at such a speed that said overrunning clutch is engaged and said control shaft means turns said shock absorbing means at said selected speed whereby the speed of further movement of said reciprocable member cannot exceed the speed component of the rotary speed of said shock absorbing means in said direction of movement of said reciprocating member.

60 2. Shock absorbing apparatus comprising, in combination, control shaft means; means for rotating said control shaft means at a selected speed; supporting means; shock absorbing means mounted on said supporting means for turning movement and including an engaging member

movable along a circular path; an overrunning clutch connecting said shock absorbing means with said control shaft means and having a position of rest in which said overrunning clutch is disengaged and said engaging member is located in a first angular position; and a reciprocable member driven to move in one direction transverse to a plane passing through said engaging member in said first angular position and the center of said circular path at a speed having a predetermined ratio to said selected speed of said control shaft means and engaging said engaging member of said shock absorbing means near the end of a reciprocating stroke whereby said shock absorbing means is turned until said engaging member is located in a second angular position in which a plane passing through said engaging member and the center of said circular path extends in said direction, said shock absorbing means being turned at such a speed that said overrunning clutch is engaged and said control shaft means turns said shock absorbing means at said selected speed whereby the speed of further movement of said reciprocable member cannot exceed the speed component of the rotary speed of said shock absorbing means in said direction of movement of said reciprocating member and is zero in said second angular position of said engaging member of said shock absorbing means.

3. Shock absorbing apparatus comprising, in combination, control shaft means; means for rotating said control shaft means at a selected speed; supporting means; shock absorbing means mounted on said supporting means for turning movement; an overrunning clutch connecting said shock absorbing means with said control shaft means and having a position of rest in which said overrunning clutch is disengaged; biasing means for urging said overrunning clutch to said position of rest; and a reciprocable member driven to move in one direction at a speed having a predetermined ratio to said selected speed of said control shaft means and engaging said shock absorbing means near the end of a reciprocating stroke whereby said shock absorbing means is turned at the rotary speed of said control shaft means so that said overrunning clutch is engaged and said control shaft means turns said shock absorbing means at said selected speed whereby the speed of further movement of said reciprocable member cannot exceed the speed component of the rotary speed of said shock absorbing means in said direction of movement of said reciprocating member.

4. Shock absorbing apparatus comprising, in combination, control shaft means; means for rotating said control shaft means at a selected speed; supporting means; shock absorbing means mounted on said supporting means for turning movement and including an engaging member movable along a circular path; an overrunning clutch connecting said shock absorbing means with said control shaft means and having a position of rest in which said overrunning clutch is disengaged and said engaging member is located in a first angular position; biasing means for urging said overrunning clutch to said position of rest; a lever mounted on said supporting means for turning movement and cooperating with said engaging member so that turning of said lever will cause turning movement of said shock absorbing means out of said position of rest; and a reciprocable member driven to move in one direction transverse to a plane passing through said engaging member in said first angular position and the center of said circular path at a speed having a predetermined ratio to said selected speed of said control shaft means and engaging said lever near the end of a reciprocating stroke whereby said shock absorbing means is turned until said engaging member is located in a second angular position in which a plane passing through said engaging member and the center of said circular path extends in said direction, said shock absorbing means being turned at such a speed that said overrunning clutch is engaged and said control shaft means turns said shock absorbing means at said selected speed whereby the speed of further movement of said shock absorbing means cannot exceed the speed component of the rotary speed of said shock absorbing means in said direction of movement of said reciprocating member.

absorbing means at said selected speed whereby the speed of further movement of said reciprocable member cannot exceed the speed component of the rotary speed of said shock absorbing means in said direction of movement of said reciprocating member and is zero in said second angular position of said engaging member of said shock absorbing means.

5. Shock absorbing apparatus for a straight bar knitting machine comprising, in combination, control shaft means; means for rotating said control shaft means at a selected speed; supporting means; shock absorbing means mounted on said supporting means for turning movement; an overrunning clutch connecting said shock absorbing means with said control shaft means; biasing means for holding said clutch in a position of rest in which said clutch is disengaged; a reciprocable friction box rod driven to move in longitudinal direction thereof at a speed having a predetermined ratio to said selected speed of said control shaft means; friction box means mounted on said rod for reciprocating movement therewith; and yarn carrier means connected with said friction box means to be reciprocated by the same, said friction box means engaging said shock absorbing means at the end of a reciprocating stroke so that said shock absorbing means is turned at such a speed that said overrunning clutch is engaged and said control shaft means turns said shock absorbing means at said selected speed whereby the speed of further movement of said friction box means cannot exceed the speed component of the rotary speed of said shock absorbing means in said direction of movement of said friction box means and of said rod.

6. Shock absorbing apparatus for a straight bar knitting machine comprising, in combination, control shaft means; means for rotating said control shaft means at a selected speed; supporting means; shock absorbing means mounted on said supporting means for turning movement and including an engaging member movable along a circular path; an overrunning clutch connecting said shock absorbing means with said control shaft means; biasing means for holding said clutch in a position of rest in which said clutch is disengaged and said engaging member is located in a first angular position; a reciprocable friction box rod driven to move in longitudinal direction thereof at a speed having a predetermined ratio to said selected speed of said control shaft means, the direction of movement of said friction box rod being transverse to a plane passing through said engaging member and the center of said circular path; friction box means mounted on said rod for reciprocating movement therewith; and yarn carrier means connected with said friction box means to be reciprocated by the same, said friction box means engaging said engaging member of said shock absorbing means in said first angular position at the end of a reciprocating stroke whereby said shock absorbing means is turned until said engaging member is located in a second angular position in which a plane passing through said engaging member and the center of said circular path extends in said direction, said shock absorbing means being turned at such a speed that said overrunning clutch is engaged and said control shaft means turns said shock absorbing means at said selected speed whereby the speed of further movement of said friction box means cannot exceed the speed component of the rotary speed of said shock absorbing means in said direction of movement of said friction box means and of said rod and is reduced to zero in said second angular position of said engaging member whereby said friction box means and yarn carrier means are stopped during further reciprocating movement of said rod.

7. Shock absorbing apparatus for a straight bar knitting machine comprising, in combination, control shaft means; means for rotating said control shaft means at a selected speed; supporting means; shock absorbing means mounted on said supporting means for turning movement and in-

cluding an engaging member movable along a circular path; an overrunning clutch connecting said shock absorbing means with said control shaft means; biasing means for holding said clutch in a position of rest in which said clutch is disengaged and said engaging member is located in a first angular position; a lever means mounted on said supporting means for turning movement about an axis spaced from the center of said circular path and cooperating with said engaging member so that turning of said lever in one direction will cause turning movement of said shock absorbing means through an angle of substantially 90° out of said position of rest; a reciprocable friction box rod driven to move in longitudinal direction thereof at a speed having a predetermined ratio to said selected speed of said control means, the direction of movement of said friction box rod being transverse to a plane passing through said engaging member and the center of said circular path; friction box means mounted on said rod for reciprocating movement therewith; and yarn carrier means connected with said friction box means to be reciprocated by the same, said friction box means engaging said lever while said engaging member is in said first angular position at the end of a reciprocating stroke whereby said lever turns said shock absorbing means until said engaging member is located in a second angular position in which a plane passing through said engaging member and the center of said circular path extends in said direction, said shock absorbing means being turned by such a speed that said overrunning clutch is engaged and said control shaft means turns said shock absorbing means at said selected speed whereby the speed of further movement of said friction box means cannot exceed the speed component of the rotary speed of said shock absorbing means in said direction of movement of said friction box means and of said rod and is reduced to zero in said second angular position of said engaging member whereby said friction box means and yarn carrier means are stopped during further reciprocating movement of said rod.

8. A shock absorbing apparatus as set forth in claim 7 wherein said lever has an intermediate portion cooperating with said engaging member and an end portion engaged by said friction box means.

9. An apparatus as set forth in claim 7 wherein said shock absorbing means includes a shaft mounted for turning movement in said supporting means, a plate secured to said shaft, and a stud mounted on said plate radially spaced from the axis of said shaft, said engaging member being a roller mounted on said stud for turning movement so as to roll on said lever during movement between said angular positions.

10. An apparatus as set forth in claim 7 and including stop means on said supporting means for limiting movement of said lever against the action of said biasing means when said engaging member is in said first angular position and said clutch in said position of rest.

11. An apparatus as set forth in claim 6 wherein said overrunning clutch includes a first part connected with said shock absorbing means for turning movement therewith, and a second part connected with said control shaft means for turning movement therewith; and wherein said biasing means connect said supporting means with said shock absorbing means to turn the latter with said first part to a position in which said overrunning clutch is disengaged; and stop means on said supporting means for blocking turning movement of said shock absorbing means under the action of said biasing means when said engaging member is in said first angular position.

12. Shock absorbing apparatus for a straight bar knitting machine comprising, in combination, a main drive shaft; control shaft means; transmission means connecting said main drive shaft with said control shaft means for rotating said control shaft means at a selected speed; supporting means; shock absorbing means mounted on said supporting means for turning movement; an over-

running clutch connecting said shock absorbing means with said control shaft means; biasing means for holding said clutch in a position of rest in which said clutch is disengaged; a draw cam driven from said main drive shaft; a rocker arm having cam follower means cooperating with said draw cam so as to be reciprocated; a friction box rod connected with said rocker arm and reciprocated by the same in longitudinal direction thereof at a speed having a predetermined ratio to said selected speed of said control shaft means; friction box means mounted on said rod for reciprocating movement therewith; and yarn carrier means connected with said friction box means to be reciprocated by the same, said friction box means engaging said shock absorbing means at the end of a reciprocating stroke so that said shock absorbing means is turned at such a speed that said overrunning clutch is engaged and said control shaft means turns said shock absorbing means at said selected speed whereby the speed of further movement of said friction box means cannot exceed the speed component of the rotary speed of said shock absorbing means in said direction of movement of said friction box means and of said rod.

13. A shock absorbing apparatus as set forth in claim 25 12 wherein said overrunning clutch is mounted in said supporting means and includes a first part connected to said shock absorbing means and a second part having a gear portion; and a gear mounted on said control shaft means and meshing with said gear portion.

14. A shock absorbing apparatus as set forth in claim 13 and including an elongated guide member extending parallel to said friction box rod, said supporting means being mounted on said guide member for movement along the same; and means for adjusting the position 35 of said supporting means and for holding the same in a selected position; said control shaft having longitudinally extending grooves, and said gear being mounted on said supporting means for turning movement and on said control shaft means for axial movement and having 40 means engaging said grooves.

15. A shock absorbing apparatus as set forth in claim 6 wherein said yarn carrying means includes a yarn carrier rod and yarn carriers on said yarn carrier rod; a stop secured to said yarn carrier rod; a guide member extending 45 in the direction of said yarn carrier rod and friction box rod and supporting said supporting means for movement along the same with said shock absorbing means; and stop means secured to said supporting means for movement with the same and cooperating with said stop 50 on said yarn carrier rod to stop the latter when said friction box means has turned said engaging member to said second angular position.

16. Shock absorbing apparatus for a straight bar knitting machine comprising, in combination, a main drive 55 shaft; control shaft means; means for rotating said control shaft means at a selected speed; supporting means; shock absorbing means mounted on said supporting means for turning movement; an overrunning clutch connecting said shock absorbing means with said control shaft means; biasing means for holding said clutch in a position of rest in which said clutch is disengaged; a draw cam driven from said main drive shaft; a rocker arm having cam follower means cooperating with said draw cam so as to be reciprocated; a friction box rod connected with 65 said rocker arm and reciprocated by the same in longitudinal direction thereof at a speed having a predetermined ratio to said selected speed of said control shaft means; an auxiliary cam connected with said draw cam for rotation therewith; a cam follower lever cooperating with said auxiliary cam; a rack bar connected with said friction box rod for reciprocating movement, a gear meshing with said rack bar, and reversing gear means connecting said gear with said control shaft and being operated by said cam follower lever to cause rotation of 70 said control shaft in the same direction of rotation while

said gear is turned in opposite directions during opposite reciprocating strokes; friction box means mounted on said rod for reciprocating movement therewith; and yarn carrier means connected with said friction box means to be reciprocated by the same, said friction box means engaging said shock absorbing means at the end of a reciprocating stroke so that said shock absorbing means is turned at such a speed that said overrunning clutch is engaged and said control shaft means turns said shock absorbing means at said selected speed whereby the speed of further movement of said friction box means cannot exceed the speed component of the rotary speed of said shock absorbing means in said direction of movement of said friction box means and of said rod.

17. An apparatus as set forth in claim 16 wherein said control shaft means has longitudinal grooves; wherein said reversing gear means include a bevel gear secured to said gear, and a pair of bevel gears meshing with said bevel gear; and coupling means mounted on said control shaft means non-turnably and for axial movement between two coupling positions in which one or the other of said pair of bevel gears is coupled with said control shaft means for rotation, said coupling means being connected with said cam follower lever and shifted by the same under control of said auxiliary cam.

18. Shock absorbing apparatus for a straight bar knitting machine comprising, in combination, control shaft means; supporting means; shock absorbing means mounted on said supporting means for turning movement; an overrunning clutch connecting said shock absorbing means with said control shaft means; biasing means for holding said clutch in a position of rest in which said clutch is disengaged; a reciprocable friction box rod driven to move in longitudinal direction thereof; means connecting said reciprocable friction box with said control shaft means for rotating said control shaft means in one direction at a rotary speed having a predetermined ratio to the speed of reciprocation of said friction box rod; friction box means mounted on said rod for reciprocating movement therewith; and yarn carrier means connected with said friction box means to be reciprocated by the same, said friction box means engaging said shock absorbing means at the end of a reciprocating stroke so that said shock absorbing means is turned at such a speed that said overrunning clutch is engaged and said control shaft means turns said shock absorbing means at a rotary speed corresponding to the speed of said friction box means and friction box rod whereby the speed of further movement of said friction box means cannot exceed the speed component of the rotary speed of said shock absorbing means in said direction of movement of said friction box means and of said rod.

19. Shock absorbing apparatus for a straight bar knitting machine comprising, in combination, a main drive shaft; control shaft means driven from said main drive shaft at a selected speed; an elongated guide member parallel with said control shaft means; a pair of supporting means mounted on said elongated guide member; means for securing said supporting means to said guide member in selected positions; an engaging member mounted on each supporting means for turning movement along a circular path and having a first angular position in which a plane through said engaging member and the

center of said path is transverse to said control shaft means, and a second angular position in which a plane through said engaging member and said center is parallel to said control shaft means; an overrunning clutch mounted on each supporting means and having a first part secured to said engaging member for turning movement therewith and a second part connected with said control shaft means and driven by the same; biasing means for holding said first part in a position in which said clutch is disengaged and said engaging member is in said first angular position; force transmitting member mounted on each supporting means cooperating with the respective engaging member so that movement of said force transmitting member will cause turning of said engaging member from said first angular position to said second angular position while said engaging member moves along said force transmitting member; a reciprocable friction box rod parallel to said control shaft and driven from said main drive shaft to reciprocate in longitudinal direction thereof at a speed corresponding to the rotary speed of said control shaft means and to the speed of said engaging member along said circular path when said clutch is engaged; friction box means mounted on said rod for reciprocating movement therewith; and yarn carrying means connected with said friction box means to be reciprocated by the same, said friction box means engaging said force transmitting members in said first angular position at the ends of opposite reciprocating strokes whereby the respective engaging member is turned with said first part of the respective clutch to said second angular position at the speed of said second part so that the speed of further movement of said friction box means cannot exceed the speed component of the speed of said engaging member along said circular path effective in the direction of reciprocation of said friction box means and is reduced to zero in said second angular position of said engaging member whereby said friction box means and yarn carrier means are stopped.

20. A shock absorbing apparatus as set forth in claim 19 and including cam means driven from said main drive shaft; first cam follower means cooperating with said cam means and connected with said friction box rod for reciprocating the same; second cam follower means cooperating with said cam means; said transmission means connecting said second cam follower means with said control cam shaft means for rotating the latter in one direction of rotation so that the speed of said control shaft means, and the speed of movement of said engaging member along said circular path depend on the speed of reciprocation of said friction box rod.
